UNITED STATES PATENT OFFICE.

EDUARD PETZ, OF ZELECHOWITZ, AUSTRIA-HUNGARY, ASSIGNOR TO AUSTRIAN FIRM:
FILZKORKFABRIK GESELLSCHAFT MIT BESCHRÄNKTER HAFTUNG, OF VIENNA,
AUSTRIA-HUNGARY.

A PROCESS FOR TREATING OSIER BARK.

1,148,401.

Specification of Letters Patent. Patented July 27, 1915.

Application filed February 21, 1914. Serial No. 820,196.

To all whom it may concern:

Be it known that I, EDUARD PETZ, subject of the Emperor of Austria-Hungary, residing at Zelechowitz, in Moravia, Austria-Hungary, have invented certain new and useful Improvements in a Process for Treating Osier Bark, of which the following is a specification, reference being had therein to the accompanying drawing.

- 10 The present invention relates to the utilization of osier bark and the object of the present invention is to provide a method of utilizing the bark of osiers whereby a spinable fiber and also insulating materials 15 and a filling material for linoleum masses are obtained, in such a manner that it is possible to treat and prepare the whole of the bark or cortical material to produce substances of high value without any waste. 20 The bark of one-year old osier willows in which the bast fibers are still relatively tender is best suited for treatment in accordance with the present invention. These barks are stored in a moderately moist and 25 well aerated room.

The barks, which for the greater part retain their original moisture are first of all treated by steam supplied for two to three hours at a pressure of 1 to 3 atmospheres. 30 The bark is then pickled for approximately 12 hours (over night) in an alkaline soap bath and it is then passed through a Hollander machine for the purpose of separating the long fibers that have already been 35 loosened from the outer bark; this machine consists of a cylinder covered with obtuse crushing members from which the bark is drawn over a stone foundation in crushing and scraping it. The long spinning fibers 40 are then separated from the short fiber material. From the latter the finer constituents are separated by sifting and these are ground to powder and utilized in substitution of cork flour while the coarse fibrous 45 material is pressed into insulating plates or which may be quilted to form felt like plates or the like. The long fibers are still somewhat brittle as they leave the Hollander machine and for the purpose of obtaining a soft touch they are treated for 50 approximately half an hour with steam at 3 to 4 atmospheres saturated with glycerin, whereupon they are dried by means of hot air. By means of these operations a very 55 high-grade, firm, pliable spinning fiber is

obtained which is similar in touch to sheep's wool.

The accompanying drawings illustrate an installation for carrying the process according to the present invention into practice in a continuous operation; the material is supplied to this installation by means of a stream of water which carries it through the various mechanisms in correspondence with the order of the operations to be effected. For the sake of compactness in their representation, the several mechanisms are shown arranged in series while in reality they are arranged in tiers.

Figure 1, is a side elevation of parts of the device partly in section. Fig. 2 illustrates a detail drawn to a larger scale.

In carrying the invention into effect as illustrated the bark is placed in receptacles *a*, two or more of which can be arranged side by side; water is admitted to those receptacles from a reservoir *o* at a higher level, which is constantly supplied through a pump pipe *m*, the branch pipe *n* being suitably adjusted for supplying the several receptacles. The latter are then closed, the cock *l* of the steam pipe opened and the bark material is treated with steam at a pressure of 2 atmospheres for from 1 to 3 hours. When the supply of steam is cut off cooling to approximately 50° C. is effected 80 and soap and soda are introduced into the receptacles *a* in such quantities that a bath of approximately 3% of soap and 1% of soda is obtained and the bark material is pickled in this bath at the temperature indicated for about 12 hours. By means of these two operations of steaming and pickling the pliability of the finer bast fibers is increased without injuring them, the outer layer of bark is to a great extent detached, the tannin leached out and the bark as a whole is prepared for the crushing process. 90

After discharging the pickling bath (through *y*) the slide *t* of the receptacle *a* is drawn up and the material flows gradually out of the receptacle *a* when the cock *n* is slightly opened; the material descends in a chute *h* to the Hollander trough *g* between two fluted cylinders *w* which are loosely in mesh and serve to give the material a preliminary crushing and convey it to the Hollander cylinder proper *u* whose obtuse knives draw the material over a foundation *v* of roughened sand stone. As at the same time 100

the material is still retained by the fluted cylinders *w* it experiences a vigorous crushing and scraping on the foundation *v* while at the same time it is stretched, whereby complete detachment of the bast fibers from the outer bark and simultaneously the separation of the long fibers is effected. From the reservoir *o* another conduit *j* leads into the Hollander trough and serves to supply a larger quantity of water when required.

At the end of the Hollander trough a rockable rake *r* is arranged and serves to retain the long spinning fibers, while the short fibrous material collects with the bark dust in the chamber *i*. As soon as a suitable quantity of bark has passed through the Hollander machine, the short material is carried by the water into the mixer *c*, when the bottom valve *k* is lifted, while the long fibers are lifted out by means of the rake *r*. These fibers are now placed in a steam-tight steam chest, steamed for about half an hour with steam at from 3 to 4 atmospheres saturated with glycerin and finally dried by means of hot air.

The waste material is discharged from the mixer *c* by opening the cock *r*, into a trough *d* divided by a sieve *a*; the dust collects in the lower compartment of this trough and is discharged therefrom with water and separated by filtration. The dust is then dried and ground and in this condition constitutes an advantageous substitute for cork flour, particularly as a filling material for linoleum masses.

The fibrous material is lifted out of the upper part of the reservoir *d* by means of scoop or dipper gear. The arms *e* of this gear carry at their end sieve plates *e'* upon which the dipper frames *l* are detachably mounted in the manner indicated in Fig. 2. During immersion the dipper frames fill with fibrous material and as soon as they reach the horizontal position they are removed from the sieve-plates and are directly brought into the press *p* in which the material is pressed. The frame and the briquet or block are then displaced laterally over the opening *g* in the press table and the

block is knocked through this opening. The 50 empty frame is then again inserted in the dipper gear. Preferably a plurality of presses *p* are appropriately grouped around the tank *d*. The briquets are then either dried directly and can be used in this form 55 for insulating purposes and the like, for which they are eminently suited owing to their high heat insulating capacity in conjunction with low specific weight; they can also be quilted into felt like plates.

Having now particularly described and ascertained the nature of my said invention and in what manner the same is to be performed, I declare that what I claim is:

1. A process for simultaneously obtaining 65 spinning fibers, insulating material and cork flour, from the bark of osiers in which the bark is first steamed at a slight excess of pressure and then pickled in an alkali soap bath, then drawn in a wet state under pressure 70 in order to separate the long fibers from the outer bark, then subjecting the material to a crushing and scraping treatment, the outer bark is then removed and the long fibers are treated with steam saturated with 75 glycerin and finally dried by means of hot air.

2. A process for simultaneously obtaining spinning fibers, insulating material and cork flour from the bark of osiers, in which the 80 bark is first steamed at a slight excess of pressure and then pickled in a bath of approximately 3% of soap and 1% of soda, then drawn in a wet state under pressure in order to separate the long fibers from the 85 outer bark, then subjected to a crushing and scraping treatment, the outer bark material is then removed and the long fibers are treated with steam at from 3 to 4 atmospheres and saturated with glycerin, and 90 finally dried by means of hot air.

In testimony whereof I affix my signature in the presence of two witnesses.

EDUARD PETZ.
